Claims priority, application France Dec. 21, 1956

9 Claims. (Cl. 323—89)

The present invention relates to magnetic amplifier devices of the kind employing self-saturated magnetic amplifiers.

An object of the present invention is to provide a magnetic amplifier device, the operation conditions of which remain completely unchanged when the parameters which determine the operation of this magnetic amplifier vary, for example in the case of temperature variation, feed voltage variation or control voltage variation. Accordingly the invention provides a magnetic amplifier device having adapted compensation, wherein there are provided at least two magnetic amplifiers, the first of which performs the function of a pilot or control amplifier, while the second is subject to the regulation of the first, the first magnetic amplifier effecting an automatic polarisation or biasing of the second magnetic amplifier, and wherein the output circuit of the pilot amplifier through which direct current flows, comprises in series, an inductance and a feedback winding wound on the magnetic circuit of said pilot amplifier, and the output of this feedback winding is connected to a polarising winding wound on the magnetic circuit of the regulated amplifier.

In order that the invention may be more clearly understood and readily carried into effect, two embodiments thereof will now be described with reference to the accompanying drawings, in which:

FIGURES 1, 2, 3, 4, 6 and 8 are curves illustrating the operation of the magnetic amplifiers.

FIGURE 5 illustrates diagrammatically one embodiment of the invention employing two amplifiers.

FIGURE 7 is a diagram illustrating the operation of the arrangement according to FIGURE 5.

FIGURE 9 illustrates diagrammatically a further embodiment of the invention.

FIGURE 10 is a diagram illustrating the operation of the arrangement according to FIGURE 9.

By way of explanation it is pointed out that a self-saturated magnetic amplifier which is controlled by direct current has a characteristic curve of rectangular form such as that indicated in FIGURE 1 showing magnetic flux as a function of ampere-turns. Such a magnetic amplifier also possesses a characteristic curve $I_m(AT_t)$ of the form illustrated in FIGURE 2, giving the mean current I_m in the circuit of the utilisation winding as a function of the continuous ampere-turns AT_t applied to the magnetic circuit. If a "negative feedback" winding, fed by the current supplied to the utilisation circuit of the magnetic amplifier is introduced, and if N is the number of turns of this winding, then a new characteristic curve $I_m(AT_t)$ with negative feedback is deduced from the characteristic curve $I_m(AT_t)$ without negative feedback as indicated in FIGURE 3. The characteristic curve of FIGURE 4 is thus obtained.

Referring to the first embodiment of the invention, the device illustrated in FIGURE 5 comprises two magnetic amplifiers A and B, the magnetic circuits of which are identical. These magnetic amplifiers are disposed together in a thermostatically controlled enclosure, and include utilisation windings e_u for A, and E_u for B, which are identical and are fed by the same alternating-current source u . RDA and RDB are rectifiers disposed in series with the winding e_u and the winding E_u respectively.

2

In order that direct current may flow in the utilisation circuit of the amplifier A, the circuit includes a filtering and regulating device consisting of an inductance L_A and a condenser C_A . A filtering and regulating device consisting of an inductance L_B and a condenser C_B in the utilisation circuit of the amplifier B is optional. Impedances Y and Z are inserted, one as an adjusting impedance in the utilisation circuit of the amplifier A and the other in the utilisation circuit of the amplifier B.

10 The amplifier A further includes a negative feedback winding e_{cr} having N turns connected to the inductance L_A , and the amplifier B includes a polarising or biasing winding E_p having N turns, the latter winding being fed by the current of the utilisation circuit of the amplifier A.

15 The characteristic curve $I_m(AT_t)$ of the amplifier B has the form indicated in FIGURE 2, and, if the amplifier A had no negative feedback winding it would have a similar characteristic curve. However, by reason of the negative feedback, the characteristic curve of the amplifier A has the form shown in FIGURE 4. Hence, there being no polarisation applied to the amplifier A, if I_{mA} is the current supplied into the utilisation circuit of the amplifier A and I_p the current in the polarising winding of the amplifier B, then $I_{mA}=I_p$ and the point of operation 20 of the device A of FIGURE 5 is represented in FIGURE 4 by the point P.

25 FIGURE 6 shows how the point of operation P of the amplifier A, having negative feedback, is deduced from the point p of the characteristic curve $I_{mA}(AT_t)$ without negative feedback. In the figure:

AT_o represents the ampere-turns corresponding to half the width of the hysteresis loop.

30 $pP=AT_o$, or by construction $pP=NI_{mA}=NI_p$, whence:

$$35 I_p = \frac{AT_o}{N}$$

It follows that the current in the polarising winding E_p of the amplifier B is such that the polarisation of this amplifier will be, in absolute value,

$$40 N \frac{AT_o}{N} = AT_o$$

45 If the direction of the winding E_p is appropriately chosen, this polarisation will be equal to $-AT_o$ in algebraic value, as is indicated in FIGURE 8. An automatic biasing or polarisation of the amplifier B is thus effected, so that the current which it supplies is its minimum current I_{oB} , commonly called the residual current. If for any reason, such as temperature variation or variation 50 of the alternating voltage, etc., the characteristic curve $I_{mB}(AT_t)$ shifts in such manner that the vertical portion of this curve remains parallel to itself and the polarisation of the magnetic amplifier B will be automatically modified, so that the inoperative point will always be at 55 the point at which the current supply I_{mB} is minimum.

55 As is shown by FIGURE 7, the characteristic curve $I_{mA}(AT_t)$, having no negative feedback, has shifted by the quantity ΔAT_t , in the same manner as the characteristic curve $I_{mB}(AT_t)$, since the two amplifiers are subject to the same temperature and feed conditions. The new current I_{pa} supplied by the amplifier A is such that:

$$I_{pa} = \frac{AT_o}{N} - \Delta \frac{AT_t}{N}$$

65 The polarisation of the amplifier B then becomes:

$$60 N \left[-\frac{AT_o}{N} + \Delta \frac{AT_t}{N} \right] = -AT_o + \Delta AT_t$$

65 The new point of operation of the amplifier B is therefore the point R_a .

70 In the foregoing, it has been assumed that the amplifier B has its inoperation point at the minimum current

supplied, namely R . However, it may be desired that the inoperative point should be fixed by an additional polarisation at R_1 , as shown in FIGURE 8.

If ampere-turns $N_c I_c$ are then applied to an amplifier such as B by a control winding E_c of resistance R fed by a direct voltage U_c , the point of operation of the amplifier B will move from R_1 to Q_1 as shown in FIGURE 8. If, under these conditions, the control voltage U_c varies, and becomes for example equal to $U_c - \Delta U_c$, the control ampere-turns become

$$N \frac{U_c - \Delta U_c}{R}$$

The new point of operation Q_{1a} may be situated to the left of the point R , for example at Q_{2a} in FIGURE 8, and the operation of the magnetic amplifier is modified, i.e., the control voltage $U_c - \Delta U_c$ is incapable of shifting operation past the biasing value $-AT_0$ and the output current I_{mB} cannot shift from R_1 to Q_1 .

The embodiment of the device as illustrated in FIGURE 9 obviates this disadvantage. There has been provided on the amplifier A , a polarising winding e_c having n_c turns of resistance r_c . This winding is continuously supplied with a voltage U_c , while the control winding E_c of the amplifier B is supplied with this voltage only at the desired instant, this being effected by any appropriate device. (In FIGURE 9, this device is diagrammatically represented by a switch IR .)

As is shown by FIGURE 10, the current I_{mA} supplied by the amplifier A is represented by the point P_1 , from which is deduced the inoperative point R_1 of the amplifier B . If the control voltage U_c varies, taking the value $U_c - \Delta U_c$, the ampere-turns of the winding e_c become

$$n_c \frac{U_c - \Delta U_c}{r_c}$$

The point of operation P_1 of the amplifier A moves to P_{1a} and, under these conditions, the inoperative point R_1 of the amplifier B moves to R_{1a} .

When the new control voltage $U_c - \Delta U_c$ is applied to the control winding E_c of the amplifier B , the point of operation of this amplifier moves to Q_{1a} . It is then possible to write, with reference to FIGURE 10:

$$rr_1 = \frac{P_{1a}}{N} = \frac{n_c i_c}{N} = \frac{n_c U_c}{N r_c} = k U_c$$

Similarly

$$rr_{1a} = \frac{P_{1a} p_{1a}}{N} = k(U_c - \Delta U_c)$$

whence

$$\frac{rr_{1a}}{rr_1} = \frac{U_c - \Delta U_c}{U_c}$$

and

$$rq_1 = r_1 q_1 - r_1 r = N_c \frac{U_c}{R} - k U_c = (k_1 - k) U_c$$

$$rq_{1a} = r_{1a} q_{1a} - r_{1a} r = (k_1 - k) (U_c - \Delta U_c)$$

finally

$$\frac{rq_{1a}}{rq_1} = \frac{rr_{1a}}{rr_1} = \frac{U_c - \Delta U_c}{U_c}$$

As long as ΔU_c is smaller than U_c , the points R_1 and R_{1a} are on one side of the vertical of the point R , and the points Q_{1a} and Q_1 on the other side of the said vertical. Therefore, the amplifier B continues to operate under the same conditions when the voltage U_c varies. This procedure may be adopted for as many control voltages U_c as desired. It is important to note that no restrictive hypothesis has been made regarding the nature of the load impedances Y and Z of the utilisation circuits of the amplifiers A and B . Notably the load impedance Z may consist of the input impedance of a four terminal network or any equivalent device.

Finally, it will readily be appreciated that it is thus possible to control a whole chain of amplifiers such as B by means of a single amplifier such as A , provided only that the amplifiers $B_1, B_2 \dots B_n$ bear the same ratio to A as does B , the utilisation winding of A feeding into the series polarising windings of the amplifiers $B_1, B_2 \dots B_n$. We claim:

1. A magnetic amplifier device having adapted compensation, wherein there are provided at least two magnetic amplifiers each having an output circuit, the first of which performs the function of a control amplifier, while the second is subject to the regulation of the first, a load connected in series with the output circuit of only the second magnetic amplifier, the first magnetic amplifier having its output circuit connected to effect an automatic biasing of the second magnetic amplifier, and wherein the output circuit of the control amplifier, through which circuit direct current flows, comprises in series, an inductance and a feedback winding wound on the magnetic circuit of said control amplifier, and a biasing winding wound on the magnetic circuit of the regulated amplifier connected to said feedback winding in the output circuit of said first magnetic amplifier.

2. A device as claimed in claim 1, wherein the magnetic amplifier subject to regulation is biased so as to supply its minimum current.

3. A device as claimed in claim 2, wherein an adjusting impedance is disposed in series with the biasing winding of the regulated amplifier.

4. A device as claimed in claim 3, wherein the control magnetic amplifier further comprises a biasing winding connected to a source of direct current and the magnetic amplifier subject to regulation further comprises a control winding, which control winding includes means for selectively energizing the same from said direct current source.

5. A device according to claim 4, wherein the magnetic circuits of the amplifiers are identical.

6. A device according to claim 5, wherein the magnetic amplifiers are arranged in the same thermostatically controlled chamber.

7. A device according to claim 6, wherein the first magnetic amplifier controls a plurality of second amplifiers, the biasing windings of the latter being connected in series in the output circuit of the first amplifier.

8. A device according to claim 7, wherein the same parameters determine the operation of all the amplifiers.

9. A magnetic amplifier device comprising a control magnetic amplifier and at least one magnetic amplifier subject to regulation, each magnetic amplifier including a saturable magnetic circuit, a main winding wound on said saturable magnetic circuit with each main winding having a respective rectifier connected in series therewith to a source of alternating current, a feedback winding wound on the saturable magnetic circuit of the control magnetic amplifier with an impedance connected in series therewith to the main winding and rectifier of the control magnetic amplifier, and a biasing winding wound on the saturable magnetic circuit of each magnetic amplifier subject to regulation and connected to the feedback winding of the control magnetic amplifier and fed by output current of the control magnetic amplifier to insure automatic biasing continuously regulating the respective magnetic amplifier subject to regulation, each magnetic amplifier subject to regulation having a separate load connected in series with the main winding and rectifier of only the respective magnetic amplifier subject to regulation.
